BERTWELL C. ROOT, OF BERLIN, NEW HAMPSHIRE, ASSIGNOR TO BROWN COMPANY, OF BERLIN, NEW HAMPSHIRE, A CORPORATION OF MAINE.

TUBULAR BEND AND METHOD OF MAKING SAME.

Application filed January 24, 1927. Serial No. 162,946.

This invention relates to tubular bends, and has for its object the production of such bends from straight tubes, and more particularly from tubes formed from fiber such as wood pulp.

Such tubes may be produced by winding a web of pulp from a Fourdrinier wire or other web-forming mechanism, on a mandrel until a wall of the desired thickness has been built up, whereupon the tube is removed from the mandrel and thoroughly dried. The convolutions of a tube thus produced are sufficiently interfelted or matted together to constitute a substantially homogeneous or non-laminated wall. When used as a pipe for fluids or as a conduit for electric wiring systems, it is customary to treat the tubes with a thermo-plastic waterproofing material, e. g. pitch, in a manner to permeate the same, thereby also strengthening and rigidifying the same, and increasing their dielectric properties.

In installing a pipe or conduit system, bends of various curvatures are sometimes necessary. This invention provides a simple and economical method of making sound, well-appearing bends from straight fiber tubes.

In accordance with the method of the present invention, a series of wedge-shaped cutouts are formed in the wall of the straight tube prior to its treatment with waterproofing material. The tube is then bent until the adjacent ends of the sections formed by the cutouts substantially abut, whereupon the sections are fixed in this position. The bend is then treated with a thermoplastic waterproofing material to effect its permeation with such material. This treatment also produces an intimate bonding of the ends of the sections, so that the resulting bend is rigid, durable, and not liable to leakage.

The invention may best be understood from the following more detailed description thereof, when considered in conjunction with the accompanying drawings, wherein

Figure 1 represents in front view a straight fiber tube having cutouts formed therein and conditioned for bending.

Figure 2 is a similar view, showing the manner in which the tube is bent.

Figure 3 is a similar view, showing the resultant bend.

Figure 4 is a section on the line 4—4 of Figure 3.

Figure 5 represents in front view a straight tube conditioned for forming a compound bend.

Figure 6 is a front view showing the manner in which the tube is bent to compound curvature.

Figure 7 is a left end view of the resultant bend.

Referring to Figure 1 of the drawings, at 1 is indicated a straight fiber tube, as yet untreated with waterproofing material, from which the bend is to be formed. A series of spaced, wedge-shaped cutouts 2 are formed in the wall of the tube by sawing or otherwise cutting sections therefrom. Each cutout decreases in width from one side of the tube toward its opposite side 1^b, but terminates sufficiently short of the other side to leave the tube continuous. The tube as conditioned for bending thus consists of a series of sections 3 of trapezoidal form, joined together integrally at their wider base portions 4 by the tube wall. By varying the angularity of the cutouts or the width of the sections left therebetween, or both, the curvature of the resulting bend may be varied.

The tube is bent, as indicated in Figure 2, until the adjacent ends 2^b of the sections substantially abut, whereupon the sections are fixed in this position. To this end, fabric 5, such as cotton duck, is then wrapped tightly around the bend and maintains the sections against displacement. A pair of reinforcing strips or pieces 6, of the appropriate curvature, are also preferably then fastened to the bend at the bases of the sections to aid in maintaining the sections against displacement and also to strengthen or reinforce the bend where it is most liable to failure. The reinforcing strips may be and preferably are made of fibrous material and may be formed by pressing together moist interfelted cellulosic material in a mould of the proper form until it has permanently acquired the shape of the mould. The moulded pieces after being dried are fastened to the bend, preferably by wooden pegs 7 similar to those sometimes used in pegging shoes. To facilitate pegging, starting apertures of a depth less than the length of the pegs may be formed in the material, after which the pegs may be inserted

into the apertures and driven into the unperforated material. Where available, however, the usual pegging machine, which both forms the hole and drives the peg, is preferably employed.

The bend is then treated with a thermoplastic water-proofing material, e. g., pitch, in a manner to effect a permeation of the fibrous material and the bonding together of the sections at their ends. This may be accomplished by the use of a pitch of medium hardness and sufficiently liquefiable by heat at a moderate temperature to yield a liquid of the proper viscosity to penetrate the bend without burning it. The impregnation or permeation of the bend may also, if desired, be accomplished in a closed vessel under pressure somewhat greater than atmospheric pressure. Preferably, a plurality of bends are immersed in a bath of the liquefied pitch for a sufficient time, under pressure, to permit the pitch thoroughly to impregnate and permeate the wall of the bends and to fill the pores and interstices thereof and coat the fibres thereof. On removing the bends from the bath, the pitch hardens and firmly bonds together the sections at their ends, and leak-proofs them.

The method of the present invention also makes possible the production of a compound bend or one whose axis lies in more than one plane. This may be accomplished, as shown in Figure 5, by forming spaced cutouts 8, which terminate along spiral lines 9, or lines of other predetermined configuration, rather than along straight lines. When a tube thus conditioned for bending is bent so that the adjacent ends of the sections 10 abut as shown in Figure 6, a compound bend, i. e., a bend whose axis lies in more than one plane, is produced. Fabric 11 is then wrapped tightly around the bend to maintain the sections against lateral displacement, and a pair of fibrous reinforcing strips 12, moulded to the appropriate curvatures, are then pegged to the bend at the bases of the sections, whereupon the bend may be treated with pitch or other thermoplastic waterproofing material, as hereinbefore described.

Employing the method hereinbefore described, bends of considerable sharpness may be readily and economically formed. The bends thus made are not liable to leakage, and are rigid, sound and well-appearing.

Having thus described certain embodiments of this invention, it is evident that they are subject to change and modification, without, however, departing from the spirit or scope of invention as defined by the appended claims.

I claim:

1. A method of making bends from straight fiber tubes, which comprises forming a series of spaced, wedge-shaped cutouts in the wall of the tube, thereby leaving a series of sec-

tions of trapezoidal form; bending the tube until the adjacent ends of the sections substantially abut; and bonding together the abutting ends of the sections.

2. A method of making bends from straight fiber tubes, which comprises forming a series of spaced, wedge-shaped cutouts in the wall of the tube, thereby leaving a series of sections of trapezoidal form, bending the tube until the adjacent ends of the sections substantially abut, fixing the sections in this position, and treating the bend with a thermoplastic waterproofing material in a manner to bond together the abutting ends of the sections.

3. A method of making bends from straight fiber tubes, which comprises forming a series of spaced, wedge-shaped cutouts in the wall of the tube, thereby leaving a series of sections of trapezoidal form; bending the tube until the adjacent ends of the sections substantially abut; wrapping a fabric tightly around the bend to maintain the sections against displacement; and treating the bend with a thermoplastic waterproofing material.

4. A method of making bends from straight fiber tubes, which comprises forming a series of spaced, wedge-shaped cutouts in the wall of the tube, thereby leaving a series of sections of trapezoidal form; bending the tube until the adjacent ends of the sections substantially abut; fastening reinforcing strips to the bend to maintain the ends of the sections in abutment; and treating the bend with thermoplastic waterproofing material in a manner to bond together the abutting ends.

5. A method of making bends from straight fiber tubes, which comprises forming a series of spaced, wedge-shaped cutouts in the wall of the tube, thereby leaving a series of sections of trapezoidal form joined together at their wider base portions by the tube wall; bending the tube until the adjacent ends of the sections substantially abut; wrapping a fabric tightly around the bend to maintain the sections against displacement; fastening a pair of reinforcing strips of the appropriate curvature to the bend at the base portions of the sections to maintain the ends of the sections in abutment; and treating the bend with thermoplastic waterproofing material.

6. A method of making bends from straight fiber tubes, which comprises forming a series of spaced, wedge-shaped cutouts in the wall of the tube, thereby leaving a series of sections of trapezoidal form joined together at their wider base portions by the tube wall; bending the tube until the adjacent ends of the sections substantially abut, wrapping a fabric tightly around the bend to maintain the sections against displacement; pegging fiber reinforcing strips of the appropriate curvature to the bend at the base

portions of the sections; and treating the bend with thermoplastic waterproofing material in a manner to permeate the fibrous material and to bond together the adjacent ends of the sections.

7. A fibrous tubular bend, comprising a plurality of integrally joined sections bonded together in abutting end-to-end relation.

8. A fibrous tubular bend, comprising a plurality of integrally joined sections fixed and bonded together in abutting end-to-end relation and permeated with waterproofing material.

9. A fibrous tubular bend, consisting of a series of sections of trapezoidal form integrally joined together at their wider base portions and permeated and bonded together at their adjacent ends with a thermoplastic waterproofing material.

10. A fibrous tubular bend, consisting of a series of integral sections of trapezoidal form wrapped tightly about with a fabric and permeated throughout and bonded together at their adjacent ends with a thermoplastic waterproofing material.

11. A fibrous tubular bend, consisting of a series of integral sections of trapezoidal form wrapped tightly about with a fabric and exteriorly reinforced with strips, said sections being permeated throughout and bonded together at their adjacent ends with a thermoplastic waterproofing material.

12. A fibrous tubular bend, consisting of a series of integral sections of trapezoidal form tightly wrapped about with a fabric and reinforced by fibrous strips exteriorly at their

base portions, said sections being permeated and bonded together at their adjacent ends with thermoplastic waterproofing material.

13. A fibrous tubular bend, comprising a plurality of integrally joined sections bonded together in abutting relation and permeated with a thermoplastic waterproofing material, the axis of said bend lying in more than one plane.

14. A fibrous tubular bend, comprising a series of integrally-joined sections in abutting end-to-end relation and exteriorly reinforced, said sections being permeated throughout and bonded together at their adjacent ends with waterproofing material.

15. A fibrous tubular bend, comprising a series of integrally-joined sections of trapezoidal form in abutting end-to-end relation and reinforced exteriorly at their base portions, said sections being permeated throughout and bonded together at their adjacent ends with waterproofing material.

16. A fibrous tubular bend, consisting of a series of integral sections of trapezoidal form wrapped tightly about with a fabric and exteriorly reinforced.

17. A fibrous tubular bend, consisting of a series of integral sections of trapezoidal form wrapped tightly about with a fabric and exteriorly reinforced, said sections being permeated throughout and bonded together at their adjacent ends with waterproofing material.

In testimony whereof I have affixed my signature.

BERTWELL C. ROOT.
